UNITED STATES PATENT OFFICE.

ALEXANDER K. RARIG, OF SAN FRANCISCO, CALIFORNIA.

CONVEYING MECHANISM FOR CANNING MACHINES.

Application filed May 1, 1924. Serial No. 710,477.

To all whom it may concern:

Be it known that I, ALEXANDER K. RARIG, a citizen of the United States, residing at San Francisco, in the county of San Francisco and State of California, have invented new and useful Improvements in Conveying Mechanism for Canning Machines, of which the following is a specification.

This invention relates generally to improvements in conveying mechanism for canning or packaging machinery, and particularly to mechanism for conveying cans, jars or other containers through a processing chamber or other chamber in which processing, vacuumizing and sealing or other operations are performed, such, for example, as a vacuumizing chamber wherein the cans or other containers are vacuumized and sealed, or for the purpose of conveying containers to a double seamer or other working device, for hermetically sealing or otherwise treating the same after filling, without regard to the use of a vacuumizing or other chamber.

One object of the invention is to provide a conveying mechanism whereby the containers may be transferred on a straight or substantially straight line between the inlet and outlet of the vacuumizing or other chamber, so as to decrease the range of travel as well as the time period of travel of the containers.

A further object of the invention is to provide a conveying mechanism whereby the containers may be intermittently fed and held from feed motion for a predetermined time, to allow a sealing or other operation to be performed, and whereby the conveyor action may be governed to regulate the feed motion and properly center the containers with relation to a seaming or other working device, so that one and the same machine may be employed for conveying and operating upon containers of different sizes within any determined limits.

A still further object of the invention is to provide conveying means and operating mechanism therefor of a simple type adapted to positively engage and transmit conveying motion to the containers without liability of jamming of the containers or damage thereto, which conveying mechanism is of a type not liable to easily get out of order and capable of being easily driven and adjusted for exactness of operation, and in which the

parts are readily accessible for adjustment or other purposes.

With these and other objects in view, the invention consists of the features of construction, combination and arrangement of parts, hereinafter fully described and claimed, reference being had to the accompanying drawings, in which:

Figure 1 is a substantially central vertical longitudinal section through a vacuumizing and sealing apparatus in connection with which the invention is shown.

Figure 2 is a sectional plan view of the same.

Figure 3 is a sectional side elevation of the seamer and elements of the conveying mechanism.

Figure 4 is a plan view showing parts of the main drive gearing.

Figure 5 is a sectional plan view of the Geneva wheel drive mechanism for communicating motion from the main drive gearing to the conveyor.

Figure 6 is a view of the conveyor drive shaft and the conveyor drive sprocket thereon.

Figure 7 is a detail section on line 7—7 of Figure 6.

Figure 8 is a view in elevation showing the mounting of one of the conveyor guide sprockets, the feed disk and the sprocket for actuating said disk.

Figure 9 is a top plan view of a portion of the conveyor belt.

Figure 10 is a section on line 10—10 of Figure 9.

Figure 11 is a section on line 11—11 of Figure 10.

In the practical embodiment of my invention as herein disclosed, in which I have shown the invention, for purposes of exemplification, in connection with a vacuumizing apparatus, 1 designates a vacuumizing chamber in which a comparatively high vacuum is maintained in service by the action of an exhaust pump, not shown. Arranged within this chamber is a device 2 for sealing or otherwise acting upon the containers, said device being shown in the form of what is commonly known as a double-seamer. The specific construction of this seamer, any type of which may be used, is unimportant so far as the present invention is concerned, and is therefore not herein described in de-

tail, except with reference to certain parts, hereinafter mentioned, in connection with which the conveyor is designed to cooperate. The chamber 1 is provided at one side with an inlet 3 and at its opposite side with an outlet 4, and arranged within the chamber 1 is a stationary platform 5 extending across said chamber between said inlet and outlet. The containers to be introduced into the vacuum chamber are fed thereinto by means of an injector valve device 6, and after such containers are vacuumized and sealed, by means of the double seaming machine 2, they are discharged through the outlet 4 through the action of a primary discharge feed device or ejector, hereinafter described, and a coating ejector valve device 7. The valve devices 6 and 7 are of a suitable type for transferring the containers while at the same time sealing the inlet and discharge openings of the vacuum chamber against loss of vacuum. They may be of any suitable type, such as that shown in my application for patent executed of even date herewith, Serial No. 707,757, or of the type shown in my application for patent also executed of even date herewith, Serial No. 707,758, or of any other suitable type. As these injector and ejector valves are not, so far as their specific constructions are concerned, essential or important to the disclosure of the present invention, a detailed description thereof, is unnecessary. They are driven in practice from a main drive shaft 8 by shafts 9 in gear with the main drive shaft and with component shafts of the injector and ejector valves.

The platform 5 may form part of a frame structure 10 supporting the double seamer 2 and the elements of the conveying mechanism arranged within the vacuum chamber. Such conveying mechanism comprises an endless chain conveyor 11 arranged to travel around guide sprockets 12 loosely mounted on vertical shafts 13. The conveyor chain is arranged so that its stretches are disposed in the same horizontal plane and the working stretch 14 of this chain, which extends across the chamber 1 from side to side thereof, extends parallel with the platform 5 and with the line of feed of the containers moved thereby between the inlet 3 and outlet 4. An idle sprocket 15, preferably of adjustable type, is provided to engage the inactive or return stretch 16 of the chain for guiding the same in its movements and maintaining the chain as a whole taut. The chain is made up of pivotally connected link plates and rollers, and is provided at determined intervals with container engaging and feed fingers or flights 17 adapted as they become a part of the working stretch of the chain to extend laterally therefrom and overhang the platform 5, each finger being attached by a bracket 18 to adjacent

pivot members of the chain. These fingers or flights may be of any suitable form to engage the containers 19, but are preferably substantially V-shaped to adapt them for engaging containers of different diameters. As each container is introduced through the inlet 3 by the injector valve 6 it is engaged by a finger or flight 17 and shifted by a continuous single-stage motion of the conveyor along the platform 5 from the inlet 3 to a point in which it is in position to be acted on by the working elements of the seaming machine 2, during which time the action of the conveyor is arrested, and at the conclusion of which the conveyor again starts into motion and similarly shifts the container by a continuous single-stage motion along the platform 5 from the seaming point to the outlet 4 for discharge. At all times during their feed motion, and except at the time when they are acted upon by the working elements of the seaming machine 2, the containers rest upon the platform 5 and are slid along said platform by the flights 17 of the endless conveyor. By thus shifting the containers by successive intermittent single-stage motions from the inlet to the seaming machine, and from the latter to the outlet, the time period of travel of the containers and number of working actions of the conveyor mechanism are reduced, allowing a larger number of containers to be operated upon within any given time and avoiding a multiplicity of starting and stopping actions causing jolts and jars and objectionable wear and tear upon the machinery.

In the use of the invention in connection with a vacuumizing machine, as herein shown, it is to be understood that the containers are first filled by a suitable filling machine, and the lids or covers loosely applied by a suitable lid-applying machine, before being engaged and fed by the injector valve 6 into the vacuum 1. In this chamber 1 the containers are vacuumized on their travel from the inlet 3 to the seaming device, which seaming device then tightly closes and hermetically seals the vacuumized containers, after which the vacuumized and sealed containers are discharged through the outlet 4. As herein shown, the working parts of the double seamer consist of a rotary container supporting platform 20 having a beveled edge normally fitted against rotation in a receiving opening 21 in the platform 5, the wall of which is correspondingly beveled. Depending from this table is a stem 22 journaled in a bearing recess 23 in a vertically movable post or standard 24 normally held depressed and adapted to be automatically retracted by a spring 25 and to be elevated against the resistance of the spring by an actuating lever 26. Provided for cooperation with the rotary plat-

form 20 is a chuck 27 which receives and encloses the upper portion of the container when elevated by the platform 20, with which chuck coacts a vertically movable 5 ejector 28 and suitably driven seaming rolls 29, the ejector 28 being movable downwardly to release the seamed end of the container from the chuck 27 at the conclusion of the seaming operation. A spring 30 is provided 10 for cushioning the downward movement of the ejector 28, under the action of a lever 31, and assisting in retracting it, and a rod 32 couples the levers 26 and 31 for operating the post 24 and ejector 28 in unison, the 15 lever 28 being operated by certain working parts of the machine not necessary to be described. The container brought into position to rest upon the table 20 by the motion of the conveyor 11 is elevated by the 20 upward movement of the post 24, bringing the upper end of the container into the chuck 27, which is driven by suitable means to impart rotary motion to the container during which the sealing action is effected by 25 the seaming rollers 29. In this upward movement of the container in engagement with the chuck 27 the ejector 28 is forced upward and assists in forcing the container lid down tight for the sealing action, and 30 the platform 20 being released from the opening 21 is free to revolve with the container through the motion of its stem 22 in the socket 23. At the conclusion of the seaming operation, the post 24 is depressed, 35 again bringing the platform 20 down into the socket 21 in which it is wedged from rotation, and the ejector 28 is forced downward to displace the seamed end of the container from the chuck 27, as will be readily understood. During this seaming operation, 40 as stated, the conveyor remains at rest, but at the end of such operation the motion of the conveyor is resumed and the sealed container is conducted to the outlet 4 for discharge.

Mechanism is provided for intermittently driving the conveyor 11 for the purposes described. This mechanism comprises a sprocket wheel 33 carried by a vertical shaft 34, the teeth of which sprocket wheel engage the rear side of the working stretch 14 of the chain centrally between the two guide sprockets 12 and in line with the rotary container supporting table 20. In order to prevent this portion of the chain from being deflected inwardly out of a straight line by the pressure of the drive sprocket, and to ensure the proper and accurate placing of the container on the table 20, the bracket member 18 of each feed finger or flight 17 is provided with a guide rib 35 to engage a guide groove or recess 36 formed in the central portion of the platform 5, whereby the central portion or working stretch of 45 the chain is guided and positively held from

inward deflection by the drive sprocket 33. The sprocket 33 is loosely mounted on its shaft 34 and is adjustably connected with a flanged collar 37 keyed to said shaft. The flange of this collar 37 is provided at one side of its center with a series of threaded openings 38 and at the opposite side of its center with a corresponding series of dowel seats or sockets 39, the openings and seats being arranged diametrically opposite each other and equivalently spaced. An opening is provided in one side of the center of the sprocket 33 for the passage of a screw bolt 40 adapted for engagement with any of the openings 38, while the hub of the sprocket is provided at its opposite side with a dowel pin 41 adapted for engagement with any one of the dowel seats 39, by means of which bolt and dowel pin the sprocket wheel may be fixed in a desired adjusted position to the collar 37 and thereby fixed with the collar for rotation with the shaft 34. By the adjustable connection between the sprocket 33 and the collar 37 thus afforded, the sprocket wheel may be circumferentially shifted on the collar and with relation to the shaft 34 for the purpose of adjusting the chain 11 forwardly or backwardly, in other words, to advance or retard the motion of the chain, and thus regulate its feeding action with respect to the table 20 and the chuck 27 of the seaming mechanism; thereby permitting ready and convenient adjustment and regulation of the conveyor chain for properly feeding and seaming containers of different diameters with relation to the aforesaid parts of the seaming mechanism. This construction adapts one and the same conveyor to be employed by a simple adjustment requiring a minimum amount of time, 105 for feeding containers of different diameters to the seaming machine in such a manner that the working feed will be properly timed and the containers properly centered.

The shaft 34 carries a gear pinion 42 meshing with a gear wheel 43 on a transmission shaft 44, the gear 42 being fixed to the shaft 34 and the gear 43 carried by the collar 45 loose on the shaft 44. This collar 45 also carries two of the three elements 415 of a Geneva wheel intermittent drive mechanism, to wit, a transmission disk 46 provided with radial slots 47 and a locking disk 48 provided with peripheral seat recesses 49, the slots 47 and recesses 49 being equal in number to each other but arranged in staggered relation or on lines between each other. This Geneva wheel mechanism is completed by an actuating disk 50 mounted on a shaft 51 provided at its lower end 123 with a beveled gear 52 meshing with a similar gear 53 on a countershaft 54 carrying a gear 55 meshing with a pinion 56 on the main drive shaft 8, whereby the shaft 51 is positively driven and rotated continu- 130

ously in one direction. Fixed to the shaft 51 or to the disk 50 is a crank arm 57 provided with a pin or stud 58 adapted to successively engage the radial slots 47 of the disk 46 and to ride in and out of said slots in the rotation of the crank arm 57, whereby the disk 46 is positively engaged and turned a certain distance by the pin 58 and then released by the withdrawal of the pin 58 from the slot 47 with which it has been engaged. The disk 50 has a portion of its periphery cut away or recessed, as at 59, and when this cut away or recessed portion of said disk faces the disk 48, during which time the stud 58 is in engagement with one of the slots 47, the disks 46 and 48 are free to be rotated. At all other times the unreduced peripheral portion of disk 50 is adapted to engage one or the other of the seat recesses 49 of disk 48 successively to lock the parts 46, 48 and 43 against rotary motion between intervals of periodic motion of said parts by engagement of the stud 58 with the successive slots 47 of disk 46. Hence it will be seen that during a portion of each revolution of the disk 50 the stud 48 will engage one of the slots 47 and impart a part revolution to the disk 46 and through the same to the gear 43 and from said gear to the shaft 34 to impart a prescribed feed motion to the chain 11, in which operation another slot 47 is brought into position for the subsequent periodic motion, the transmission elements of the Geneva wheel motion and the conveyor chain being locked against motion during their intervals of rest so that any possible shifting of the same out of position will be prevented. The range of motion of the conveyor from the Geneva wheel mechanism on each actuation thereof may be sufficient to transfer a container from the inlet 3 to the elements of the seaming mechanism, and the preceding container from the latter to the outlet 4, and the time period of rest of the conveyor mechanism is made in practice just sufficient to permit the container which is to be seamed to be operated upon by the double seamer, as will be readily understood. During the transmission of the container from the inlet 3 to the seaming mechanism and until it is sealed by the latter, the container is subjected to the vacuumizing action within the chamber 1, whereby a thorough vacuumization prior to final sealing is effected.

The primary discharge feed device or ejector, hereinbefore referred to, for transferring the containers from the platform 5 to the ejector valve 7, comprises a horizontally disposed circular disk 60 fixed on the vertical shaft 13 located at the delivery side of the machine. This shaft is driven continuously in one direction, for imparting continuous rotary motion to said disk, by a sprocket chain 61 engaging sprocket

wheels 62 and 63 on the said shaft 13 and the shaft 51, respectively. The disk forms a horizontally rotatable delivery platform 1 sets in a segmental recess in the platform 5, flush with the upper surface of said platform, and extends through the outlet 4 into a throat or passage leading to the inlet of valve 7, said throat being normally sealed by said valve against leakage. The function of this disk is to cover the gap between the ejector valve and the container feeding flight at the delivery end of the conveyor, and to effect a smooth, even, regular and rapid movement of the containers, without injury thereto, across said gap and into the ejector valve casing for discharge. The ejector valve may deliver the vacuumized and sealed containers to a suitable shelf or receptacle or to a conveyor leading to a desired destination point.

From the foregoing description, taken in connection with the drawings, it will be seen that the invention provides an intermittently operated conveying mechanism for the purpose described which is simple of construction and of a type ensuring efficiency and reliability in action, and which is composed of parts not liable to easily get out of order. Also it will be seen that the conveyor in its operation transfers the container on a direct line across the chamber 1 between the inlet 3 and outlet 4, during which they successively pass between and are acted upon by the elements of the seaming mechanism, whereby a short range of travel for the containers is provided. It will also be seen that the containers, during their feed motion, rest upon the platform 5 and are shifted along said platform in such a way as to obviate all liability of jamming, spilling of their contents or injury to the containers themselves or the marring of their surfaces. By the provision of the means for effecting and advancing or retarding adjustment of the conveyor 11, it will be evident that the conveyor action may be regulated to operate upon containers of different diameters and to properly time their working feed and center them with relation to the working parts of the seaming mechanism. In practice a suitable opening, or hand hole closed by a hand-hole plate or cover, may be provided in the chamber 1 to permit convenient access to be obtained to the parts for various purposes, and to admit of the adjustment of the sprocket wheel 33 for the purpose described in an easy manner and within a comparatively short period.

While the invention has been shown and described for use in vacuumizing machines, in connection with which it is particularly designed and adapted, it is to be understood that it is not restricted in use thereto, but may be employed in other types of apparatus in which a feed motion of the same

character is to be employed, and accordingly it is to be understood that the invention is not restricted in use except when particularly restricted as specified in certain of the appended claims.

Having thus fully described my invention, I claim:

1. In mechanism for shifting containers from a receiving position to a work device and from a work device to a discharge position, a stationary platform extending between said positions and past said work device; an endless chain conveyor having its stretches arranged in the same horizontal plane and having its working stretch movable in a plane parallel with the platform, fingers on the conveyor operative when becoming a part of the working stretch of said conveyor to extend over the platform for successively sliding containers along the platform; means for intermittently operating the conveyor so as to adapt each finger to engage and on successive straight-line motions slide a container from the receiving position to the work device and from the work device to the discharge position with an interval of rest between such motions; and a horizontally rotatable feeder arranged flush with the platform for receiving the containers therefrom on the final working motion of the fingers and slidably shifting said containers to a delivery point beyond the remote end of the platform.
2. In mechanism for shifting containers from a receiving position to a work device and from the work device to a discharge position, a stationary platform, an endless chain conveyor having its stretches arranged in the same plane and having its working stretch extending parallel with the platform, fingers on said conveyor operative when becoming a part of the working stretch thereof to engage and slide the containers along the platform; drive mechanism for intermittently operating the conveyor, said mechanism including a gear engaging the working stretch of the conveyor in line with the work device and on the side of said working stretch opposite said work device, and means for guiding and holding the working stretch from deflection under the pressure of said gear.
3. In mechanism for feeding containers from a receiving position to a work device and from the work device to a discharge position, a stationary platform along which the containers are supported on end and adapted to slide, an endless chain conveyor having its stretches arranged in the same horizontal plane and having its working stretch extending parallel with the platform, fingers on the conveyor operative when becoming a part of the working stretch of the conveyor to overhang the platform and slide the containers there-
- along, mechanism for intermittently operating the conveyor including a gear and a shaft on which the gear is adjustably mounted and to which said gear is adapted to be fixed, whereby the conveyor may be advanced or retarded in its working motion for centering containers of different sizes with relation to the work device, said gear being arranged to engage a surface of the working stretch of the chain opposite the work device, means for guiding the working stretch of the chain and holding it from deflection under pressure of the gear, a horizontally rotatable feeder lying flush with the delivery end of the platform for receiving and conveying the containers therefrom, and means for continuously driving said feeder.
4. In mechanism for feeding containers from a receiving position to a work device and from the work device to a discharge position, a framework including a stationary platform extending beneath and on opposite sides of said work device, an intermittently movable endless chain conveyor having a working stretch extending along one side of and parallel with the platform and provided with fingers extending over the platform for engaging and feeding the containers along the platform from the inlet to the work device and from said work device to the outlet, means including a drive gear engaging the working stretch of the chain in the region of the work device for imparting intermittent feed motion to said chain, means for adjusting said gear for advancing or retarding the conveyor chain, and means for guiding the working stretch of the chain in the region of the gear and holding it from lateral deflection under pressure of said gear.
5. In mechanism for shifting containers across a chamber from an inlet at one side of the chamber to an outlet at the diametrically opposite side thereof and past a work device disposed in said chamber between said inlet and outlet, a stationary platform extending beneath the work device and across the chamber for slidably supporting the containers for feed motion, an endless conveyor having a working stretch extending along one side of said platform and parallel therewith and provided with fingers projecting over said platform for engaging and transmitting sliding motion to the containers, said working stretch of the chain being arranged to transmit the containers by successive continuous single-stage substantially straight-line motions respectively from the inlet to the work device and from the work device to the outlet, a drive gear engaging the working stretch of the chain at a point substantially in transverse alignment with the work device, means

- for guiding the working stretch of the chain and holding it from deflection under the pressure of said gear, and mechanism of which said drive gear forms a part for 5 intermittently actuating said conveyor chain for imparting the successive continuous substantially straight-line feed motions described with a dwell or interruption of motion between the same, during which 10 dwell or interruption of motion the container fed up by the first-named single-stage substantially straight-line motion is acted upon by the work device.
6. In mechanism for shifting containers between the inlet of a chamber and a working device arranged therein and between said working device and the outlet of the chamber, an intermittently movable endless conveyor for feeding containers from the inlet to the working device and from the latter to the outlet, means for intermittently actuating said conveyor, and a continuously rotatable feed disk located adjacent to said outlet and driven independently of said conveyor for receiving the containers from the conveyor and feeding the same through the outlet.
7. In mechanism for shifting containers between the inlet of a chamber and a working device arranged therein and between said working device and the outlet of the chamber, an intermittently operable endless chain conveyor having a continuously straight working stretch for shifting containers from the inlet to the working device and from the latter to the outlet, an intermittently movable drive gear engaging the rear surface of such working stretch of the chain conveyor in line with the working device, a stationary guide member, and means on the conveyor chain for engagement with said guide member for guiding the working stretch of the conveyor and holding it from deflection under the pressure of the drive gear.
8. In mechanism for shifting containers between the inlet of a chamber and a working device arranged therein and between said working device and the outlet of the chamber, an intermittently operable endless chain conveyor having a continuously straight working stretch for shifting containers from the inlet to the working device and from the latter to the outlet, a rotary disk feeder located adjacent to the outlet for shifting the containers from the delivery end of the platform through the outlet, an intermittently 15 movable drive gear engaging the rear surface of such working stretch of the chain conveyor in line with the working device, and means for guiding the working stretch of the conveyor and holding it from deflection under the pressure of the drive gear.
9. In mechanism for shifting containers between the inlet of a chamber and a working device arranged therein and between said working device and the outlet of the chamber, an intermittently operable endless chain conveyor for shifting the containers from the inlet to the working device and 20 from the latter to the outlet, and a continuously rotatable horizontally disposed circular feed disk for receiving the containers from the conveyor and delivering them through the outlet.
10. In mechanism for shifting containers between the inlet of a chamber and a working device arranged therein and between said working device and the outlet of the chamber, a platform, an intermittently operable endless conveyor provided with fingers for engaging and slidably shifting the containers along said platform from the inlet to the working device and thence to the outlet, a Geneva wheel mechanism for intermittently operating said conveyor, a continuously rotatable feed device for receiving the containers from the delivery ends of the platform and the conveyor and discharging the same through the outlet, said feed device 25 extending partially beneath the delivery end of the conveyor, and means independent of said Geneva wheel mechanism for operating said rotatable feed device.
11. In mechanism for shifting containers between the inlet of a chamber and a working device arranged therein and between said working device and the outlet of the chamber, an intermittently operable endless conveyor having a working stretch operative 30 for shifting the containers from the inlet to the working device and thence to the outlet, a drive sprocket engaging said working stretch of the chain, means for adjusting said drive sprocket for advancing or retarding the motion of the chain, a stationary guide, means on the chain engageable with said guide for holding the working stretch of the chain from deflection under pressure from said drive sprocket, and a Geneva wheel mechanism for intermittently actuating said drive sprocket.

In testimony whereof I affix my signature.
ALEXANDER K. RARIG.
